UNITED STATES PATENT OFFICE

2,608,970

SURGICAL TRUSS WITH ADJUSTABLE PAD

William L. Conner, Philadelphia, Pa.

Application November 19, 1949, Serial No. 128,462

4 Claims. (Cl. 128—110)

1

This invention relates to surgical trusses for hernias or the like and one object of my invention is to provide an improved truss that is highly effective in applying a desired degree of localized pressure on the hernia without discomfort to the user. A further object is to have a high degree of flexibility of application so that the truss may be applied with equal facility to different body contours.

Another object is to provide an improved truss having the foregoing characteristics as well as being relatively simple, compact and readily disassembled and assembled so as to insure maximum cleanliness and ease of operation.

While a great many types of trusses have been heretofore suggested and used, yet they have been deficient either functionally, structurally, or economically.

Other objects and advantages will be apparent to those skilled in the art from the following description of the accompanying drawings in which:

Fig. 1 is an elevational view of my improved truss showing the straps broken away;

Fig. 2 is a top plan view of my improved pressure applying element;

Fig. 3 is a transverse section taken substantially on the line 3—3 of Fig. 1 showing my improved pressure element and substantially its minimum pressure position;

Fig. 4 is a sectional view similar to Fig. 3 showing the pressure element and substantially its maximum pressure position; and

Fig. 5 is a perspective of a plastic pad.

In the embodiment of my invention shown in Figs. 1 to 4, I have provided a usual body belt 1 and leg straps 2, it being understood that the device as shown is for single hernia application, although a double hernia arrangement can be provided merely by duplicating the pressure element in the customary manner. Hence, the double hernia arrangement is not shown. The pressure element, generally indicated at 3, consists of a belt base 4 secured by screws 5 to a flat metal belt plate 6 which in turn is secured to the body belt 1 by rivets 7. The belt base 4 generally follows the external configuration of plate 6, while an inner sealing surface 8 of semi-spherical shape, preferably concave, terminates in a circular opening 9. A ball swivel 10 has a semi-spherical convex surface 11 seated on seat 8. This ball swivel serves as a movable connection for a body pressure ball element 12. A normally flat circular pad 13 of sponge plastic is supported on the semi-spherical convex surface of the pressure element 12 which has a recess 14

2

formed in the center of its circular flat back surface. The pad 13 is held in position by a thin plastic cover 15 which extends entirely over the pad and thence inwardly between the flat back of ball swivel 10 and a circular cover clamp 16 which is flat on both sides, the clamp 16 and ball swivel 10 thereby comprising a clamping means. The edge surface of the clamp is slightly tapered to allow the cover 15 to extend smoothly from between the ball and clamp as well as to center the clamp and pinch the cover against a slightly flared centering rim 17 of the ball swivel. If desired, the edge 18 of the plastic cover may be provided with a drawstring to hold the plastic pad and cover initially in position. To exert clamping pressure on the cover, the clamp 16 is provided with a small hub 19 having a threaded bore for receiving a combined clamping and pressure adjusting screw 20 which extends into recess 14 for abutting the bottom thereof but without having threaded engagement therewith. The screw head engages a locking plate 21 curved in semispherical shape to conform to the similarly curved surface of an extension lip 22 of casing 4. Thus, by tightening screw 20, plate 21 is pulled against base 4 and simultaneously cover clamp 16 is pulled toward ball 10 to clamp the cover membrane 15 and also to pull swivel ball 10 firmly against seat 8 of base 4. All of the elements are thereby secured together as a single rigid unit through the simple expedient of a single operating element such as screw 20 which thus constitutes means common to the operation of the clamping and pressure adjusting elements. After the pad is initially held in position on pressure ball 13 by tying cover 15 around the back of clamping plate 16 and before screw 20 is completely tightened, the user may then readily adjust elements 10, 16, 13, 12 and 15 as a single unit in any angular direction desired within the limits of the spherical surfaces of seat 8 and ball swivel 10. In this manner the pad 13 may apply pressure on the user's body in a direction that is most effective for the particular contour of the body whether the person be stout so as to require an upward pressure, as shown by the dotted line position 23 of pad 13, or thin so as to require an adjustment to the dotted line position 24. Adjustments may be obtained for various intermediate positions as well as different laterally angular positions depending upon whether pressure is to be applied in a sidewise direction. All of these vertical and lateral positions of adaptation are readily accomplished in a simple and expeditious manner by my improved device and

the finally selected position can be permanently maintained simply by tightening screw 20 to force clamping plate 21 tightly against lips 22.

To obtain different degrees of pressure, a longer screw 26, Fig. 4, may be employed whereby upon tightening this screw it will force pressure ball 12 outwardly thereby creating a greater body pressure with no change in adjustment of belt 1. The plastic cover 15 will either stretch or slip slightly beneath clamp 16 to accommodate the extended position of pressure ball 12, or the plastic pad 13 will yield sufficiently at its outer corner under the tension of cover 15 to compensate for the extended pressure position. Any number of screws of different length may be supplied to the user so that he may conveniently effect any desired degree of pressure.

From the foregoing disclosure, it is seen that I have provided a pressure device for a truss that embodies many desirable structural and functional characteristics, including adaptation to body contours, selection of degree of pressure and simplicity of operation, compactness and sanitation, all of which will insure a maximum degree of satisfaction and comfort to the user. The elements such as casing 4, swivel 10, clamp 16 and pressure ball 12 can be readily manufactured out of Bakelite or other plastic material if desired. Their shape and size are such as to lend themselves to be made readily and economically in simple molds, although it is obviously understood that other materials such as metals or the like may be employed if desired.

It will, of course, be understood by those skilled in the art that various changes may be made in the construction and arrangement of parts without departing from the spirit of the invention as set forth in the appended claims.

I claim:

1. A pressure device for a truss comprising, in combination, a base having a semi-spherical seat, a body pressure applying ball, a pad and a cover therefor mounted on said ball, clamping means interposed between said seat and ball for clamping said cover around the pad, and means for commonly holding said clamping means to the base and for simultaneously moving the pressure applying ball outwardly.

2. The combination set forth in claim 1 further

characterized in that the holding means includes a locking plate engageable with the side of said base opposite to that on which the semi-spherical seat is formed and a screw extends through said plate and has threaded engagement with said clamping means so that tightening of the screw causes the locking plate and clamping means to be firmly drawn to the opposite sides of the base.

3. The combination set forth in claim 1 further characterized in that the base has a semi-spherical outer surface concentric with the semi-spherical seat, and the holding means includes a semi-spherical locking plate engageable with said outer surface of the base for spherical movement relative thereto and a screw extends through said plate and has threaded engagement with said clamping means to draw the latter and plate together.

4. A truss device for applying localized pressure to a hernia comprising, in combination, a base normally supported on a body belt, a pressure ball, a plural part clamping means interposed between said base and ball but separate from each of the same, a cover enclosing said ball and extending between the plural parts of the clamping means to be held thereby, and a screw extending through said base and threaded into said clamping means to draw the same to said base, said screw extending through and beyond said clamping means to engage the pressure ball to force the same relatively away from the clamping means while the latter is being drawn toward the base.

WILLIAM L. CONNER.
